UNITED STATES PATENT OFFICE

FRANK JARDINE, OF CLEVELAND, OHIO, ASSIGNOR, BY MESNE ASSIGNMENTS, TO THE CLEVELAND TRUST COMPANY, AS TRUSTEE, OF CLEVELAND, OHIO, A CORPORATION OF OHIO

PISTON

Application filed February 15, 1929. Serial No. 340,088.

This invention relates to securing articles or elements of one article together and is particularly applicable to joining parts of two different metals, where the parts of an article are such that one may be made of one metallic substance and the other may be cast thereabout.

An object of the invention is to provide a simple and efficient anchorage or connection by which two elements or articles may be joined.

Other objects will hereinafter appear.

The invention will be better understood from the description of one practical embodiment thereof, illustrated in the accompanying drawings, in which:

Fig. 1 is a central longitudinal sectional view of a piston having an insert in the head thereof and attached thereto by means embodying the invention;

Fig. 2 is a central longitudinal sectional view of the piston of Figure 1 taken on the line II—II thereof, and

Fig. 3 is a bottom plan view of the piston of the above two figures.

The piston comprises a flat top or head 1 and downwardly extending cylindrical skirt 2 on the inner surfaces of which are formed piston pin bosses 3, the bosses and head being reenforced by diametrically extending webs 4 and the upper part of the skirt being provided with the usual piston ring grooves 5.

The piston illustrated is of a type made of aluminum, aluminum alloy, or similar light materials, which expands at a much higher rate than the cylinder in which it operates and, therefore, is provided with means for preventing piston slap when the parts are cold.

This means comprises a strut 6 of steel or other material which expands at a lower rate than the material of the piston and which extends diametrically across the upper part thereof its ends projecting into the bottom of one of the piston ring grooves so that the strut maintains the ring in this groove in an expanded position in which it fits the cylinder in which the piston is operating so closely that transverse movement of the piston is prevented and slap, even when the same is cold, is thereby eliminated.

In the manufacture, the strut is placed in the mold and the piston cast about the same, thus obviating the necessity for positioning and anchoring the strut after the piston has been formed. The strut consists of a flat sheet of metal 6 extending diametrically across the piston immediately under the head thereof in a plane substantially parallel to the head and in a direction at right angles to the projection of the wrist pin axis upon the same.

The strut may be provided with lightening holes 7 to reduce the weight thereof. Centrally of the strut it is provided with an aperture 8 and about the periphery of the aperture the metal of the strut is bent upwardly to form a substantially frusto-conical flange 9 so positioned that it projects toward the piston top. In casting the piston a central boss 10 depending from the head is formed thereon which imbeds the flange 9, projecting through the aperture 8.

A firm anchorage is secured by this means as any force tending to displace the strut is transmitted through the relatively large area of the flange to the boss and excessive unit stresses do not appear. Moreover the area of the aperture and the cross sectional area of the portion of the boss extending therethrough are relatively small so that differential expansion of the materials of which the strut and piston are composed do not materially loosen the connection.

While I have described the illustrated embodiment of my invention in some particularity obviously many others will readily occur to those skilled in the art to which this appertains and I do not, therefore, limit myself to the precise details shown and described, but claim as my invention all embodiments coming within the scope of the appended claims.

Claims:

1. A piston comprising a metallic element having an aperture therethrough surrounded by a flange, and an element having a different coefficient of expansion and cast with a boss imbedding said flange and extending through the aperture.

2. A piston comprising a head, a cylindri-

- cal skirt depending therefrom, piston ring grooves in the upper part of said skirt, and a transverse strut of a material having a different coefficient of expansion than the material of the piston and having its ends extending into one of the piston ring grooves, the central portion of the strut being apertured and imbedded in a boss depending from the piston head.
- 10 3. A piston comprising a head, a cylindrical skirt depending therefrom, piston ring grooves in the upper part of said skirt, and a transverse strut of a material having a different coefficient of expansion than the material of the piston and having its ends extending into one of the piston ring grooves, the central portion of the strut being apertured and flanged about the aperture and said flange imbedded in the material of said piston.
- 15 4. A piston comprising a substantially flat head a cylindrical skirt depending therefrom carrying piston pin bosses and provided on its exterior surface with piston ring grooves, a centrally depending boss of the lower surface of said head, a transversely extending strut having its ends extending into one of the piston ring grooves and its center apertured and flanged, the flange being imbedded
- 20 25 30

In testimony whereof I hereunto affix my signature this 4th day of February, 1929.

FRANK JARDINE.
